H. H. GRACEY

FLUID LIFT PUMP

Filed Oct. 21, 1922

Inventor

HARVEY H. GRACEY.

By A. L. Jackson

Attorney

UNITED STATES PATENT OFFICE.

HARVEY H. GRACEY, OF FORT WORTH, TEXAS.

FLUID-LIFT PUMP.

Application filed October 21, 1922. Serial No. 596,069.

To all whom it may concern:

Be it known that I, HARVEY H. GRACEY, a citizen of the United States, residing at Fort Worth, in the county of Tarrant and State of Texas, have invented certain new and useful Improvements in Fluid-Lift Pumps, of which the following is a specification.

My invention relates to pumps and more particularly to pneumatic pumps; and the object is to provide pumps for oil and other wells, which are simple in construction and which have very few parts and which have no leather or rubber elements to be worn out and which have no movable parts and by which all the pneumatic power supplied will be utilized in lifting the liquid out of wells and which have been demonstrated to be highly efficient in pumping generally and 20 in clearing oil wells of salt water mixed with the oil. Another advantage is that the pumps maintain sufficient liquid on the sand or on top of the sand to preserve the sand intact at the bottom of the well. Other 25 objects and advantages will be fully explained in the following description, and the invention will be more particularly pointed out in the claims.

Reference is had to the accompanying drawing which forms a part of this application.

The figure of drawing is a vertical section of the improved pumping apparatus.

In the drawing a well casing 1 is shown with the lower end provided with perforations 12 to permit the intake of oil or other liquids. An air or pneumatic chamber 2 is mounted within the casing 1. The chamber 2 has a thick integral steel cap 14 and a 40 horizontal partition 9 in the lower part thereof. A relatively large discharge tube 4 is projected through the steel cap 14 and welded thereto and constitutes a part of the discharge pipe. The discharge pipe 3 is 45 screwed into the upper end of the pipe 4 for completing the discharge passage. A nipple 6 is welded to the partition 9 and forms the escape for the liquid upwardly. The discharge pipe or tube 4 surrounds the 50 upper end of the nipple 6 and forms an annular receiving nozzle for air or other pneumatic element between the interior surface of the pipe 4 and the outer periphery of the nipple 6. A continuous annular lift is thus provided for engaging the cylindrical stream of liquid which is passing up

through the nipple 6. The liquid is thus lifted uniformly around the entire stream of liquid. Air or another pneumatic element is forced down into the chamber 4 by 60 means of a pipe 10 which is coupled to a nipple 5 which is welded in the cap 14 and projects therethrough. The part 8 of the chamber 4 which projects below the partition 9 is perforated and forms a sand screen 65 and the chamber is closed at the bottom, so that any liquid that passes into the sand screen must pass through perforations 11 in the side of the chamber. Air or another pneumatic element is let down into the sand 70 screen chamber 8 by a pipe 7 which is welded to the partition 9. The pipe 7 has an upturned nozzle 13 for stirring or agitating the sand should the sand tend to accumulate in the sand screen. With such construction, there is no disturbing of the sand in the lower part of the casing 1 and on the outside of the casing. The pipe 13 will also aid in starting liquid through the nipple 6 because the air will tend to lift the 75 liquid up to the nipple 6 which projects down into the sand screen.

Various changes in the sizes, proportions, construction and arrangement of the several parts may be made without departing from 80 my invention.

What I claim is:

1. In a well casing, a pneumatic pumping apparatus comprising an air chamber provided with an integral cap, a starting pipe suspended in said chamber and projecting through said cap and welded thereto, a discharge pipe connected to said starting pipe, said chamber being extended downwardly to form a sand screen, a perforated partition dividing said sand screen from said air chamber, a nipple projecting through said partition into said sand screen chamber and centrally into said starting pipe and spaced therefrom, a tube projected through said partition and down into said sand screen for agitating the sand with compressed air and means for admitting compressed air into said air chamber.

2. In a well casing, a chamber vertically disposed in said casing and provided with a horizontal partition dividing said chamber into a pneumatic chamber and a sand screen below the partition, a cylindrical starting pipe projecting through the upper end of said pneumatic chamber and rigid therewith and suspended therein, a discharge

pipe connected to said starting pipe, a cylindrical nipple projecting through said partition downwardly into said sand screen and upwardly and centrally in said starting pipe and forming therewith a circular receiving nozzle, means for agitating the sand in said sand screen and means for admitting compressed air into said pneumatic chamber.

3. In a well casing, a chamber vertically disposed in said casing and provided with a horizontal partition dividing said chamber into a pneumatic chamber and a sand screen below the partition, a cylindrical starting pipe projecting through the upper end of said pneumatic chamber and rigid therewith and suspended therein, a discharge
- 10
- 15

pipe connected to said starting pipe, a cylindrical nipple projecting through said partition downwardly into said sand screen and upwardly and centrally in said starting pipe and forming therewith a circular receiving nozzle, means for admitting compressed air into said pneumatic chamber, said sand screen having perforations in the side wall and having the lower end closed, and a tube communicating with said pneumatic chamber and projecting down into said sand screen and provided with a sand agitating nozzle.

In testimony whereof, I set my hand, this 1st day of September, 1922.

HARVEY H. GRACEY.
